United States Patent Office

Des. 215,652
Patented Oct. 21, 1969

215,652

WHEEL

Thomas B. Griffith, San Carlos, Calif., assignor to American Racing Equipment, a corporation of California

Filed Jan. 21, 1969, Ser. No. 15,428

Term of patent 14 years

Int. Cl. D12—14

U.S. Cl. D14—30

FIG. 1

FIG. 2

FIG. 1

FIG. 2

FIG. 3

FIG. 4

FIG. 1 is a perspective view taken from the front and right side of a wheel showing my new design;

FIG. 2 is a front elevational view;

FIG. 3 is a perspective view taken from the rear and right side;

FIG. 4 is a rear elevational view; and

FIG. 5 is a cross-sectional view taken from the plane shown in FIG. 2.

The portions of the drawings that are lined show machined surfaces, and the portions of the drawings that are stippled show cast surfaces.

I claim:

The ornamental design for a wheel, substantially as shown and described.
